WITNESS:

BY *Victor J. Evans*

ATTORNEY

UNITED STATES PATENT OFFICE

ALEX DU MENIL, OF SAN ANTONIO, TEXAS

EMERY WHEEL STAND

Application filed February 14, 1930. Serial No. 428,472.

This invention relates to guards or protectors to partially enclose grinding, buffing and scratching wheels to protect the eyes of the user.

5 Another object of the invention contemplates the provision and arrangement of an adjusting element for the guard whereby the gap or clearance between the end of the band may be varied for working clearance and 10 vision.

More specifically stated the mounting for the band and guard is adjustable whereby the entire protector may be adjusted circumferentially of the bearing and tool supporting shaft.

With the above and other objects in view, the invention further consists of the following novel features and details of construction, to be hereinafter more fully described, 20 illustrated in the accompanying drawings and pointed out in the appended claim.

In the drawings:—

Figure 1 is a vertical sectional view taken on line 1—1 of Figure 4.

25 Figure 2 is a fragmentary top plan view of the form of grinder with the invention applied.

Figure 3 is a horizontal sectional view taken on line 3—3 of Figure 1.

30 Figure 4 is a vertical sectional view taken on line 4—4 of Figure 1.

Figure 5 is a perspective view of the band.

Figure 6 is a perspective view of the guard.

35 Figures 7 and 8 are perspectives of the adaptor and adjusting element.

Referring to the drawings in detail wherein like characters of reference denote corresponding parts, the reference character 10 indicates the base of a form of grinding and 40 polishing stand having arms 11 upstanding from the ends thereof. Removably secured adjustably mounted cap bearings 12 carried upon the upper portions of the arms 11 are internally threaded, as at 13, for adjustable

45 connection with the thrust sleeves 14 of a bearing construction having its inner portion or section 15 abutting a shoulder or stop 16 upon a mandrel shaft 17. Said shaft projects outwardly an appreciable distance 50 from the bearings to accommodate a grind-

ing disk or wheel, such as indicated at 18, a buffing wheel or scratching brush, not shown. A pulley 19 being carried upon the mandrel shaft 17 in oppositely disposed relation to that of the grinding wheel or disk 18 for the accommodation of a strap or belt from a motor or line shaft. All of the above is of the usual and well known construction incident to that of the type of machine described and forms no part of the present application for Letters Patent but is merely mentioned for the purpose of illustration in bringing forward the novel advantages of the present invention.

The invention contemplates the provision of an adaptor sleeve 20 projecting for an appreciable portion of its length within the cap bearing 12 and threadedly engaged therewith. After the cap bearing has been secured in place, binding action will be set up and the bearing 14 and adaptor sleeve 20 will be lockingly retained against rotation. A washer 21 receivable upon the outwardly projecting portion of the adaptor sleeve 20 and abutting the adjacent side of the immediate leg 11 and cap bearing 12 therefor, is provided with ears 22 outwardly projecting in the manner shown in Figure 4 of the drawings. The band, mentioned in the foregoing and as indicated at 23, is split to provide a 80 gap or opening 24 through which appropriate portions of the scratch brush, buffing wheel, or grinding disk may be exposed and to facilitate projecting of the work therethrough for contacting engagement with the form of tool rotating within the confines of the band.

45 Arm members 25 are secured to the inner side edge of the band in the manner shown in Figure 5 of the drawings, that is, immediately adjacent the ends of the band and projecting in spaced parallelism therefrom whereby the aforementioned degree of clearance between the ends of the band will not be impaired.

The guard for the band has the parallel 95 legs 27 thereof disposed in overlapping relation with the outer sides of the arms 25 whereby the solid horizontally offset extremity to be hereinafter designated by the reference numeral 28 is designed to regulate the 100

- amount of clearance or gap between the ends of the split band without requiring the diminishing of the initial diameter of the band. The guard 28 may be also employed as a 5 form of rest upon which tools may be disposed for sharpening and other operations. A nut 29, threadedly mounted upon the outermost projecting end of the exteriorly threaded adaptor sleeve 20 and abutting the inner 10 sides of the arm members 25 is provided with a plurality of openings 30 in the wrench engaging faces thereof for the accommodation of a nail, the shank of scribing tool and the like whereby the entire attachment may be 15 adjusted about the form of tool carried upon the mandrel shaft. This means of adjustment is necessary in view of the lack of space necessary for the accommodation of a wrench to effect such adjustment.
- 20 The invention is susceptible of various changes in its form, proportions and minor details of construction, and the right is herein reserved to make such changes as properly fall within the scope of the appended 25 claim.

Having described the invention, what is claimed is:—

- An emery wheel attachment comprising a 30 split band, an adaptor supported upon the wheel mounting, a guard having a portion extended over the split ends of the band to regulate the amount of wheel exposure, arms carried by the band and guard and extended about said adaptor, a washer receivable upon 35 the adaptor having ears projecting therefrom and restricting excessive movement of said guard and abutting the arms of the band, and an adjusting element mounted upon the adaptor having engagement with the arm 40 members of the band to lockingly retain the band and guard against accidental displacement.

In testimony whereof I affix my signature.
ALEX DU MENIL.
